LIQUID COOLED MUFFLER

Karl W. Schreeck, Cleveland, Ohio

Application November 28, 1949, Serial No. 129,785

5 Claims. (Cl. 181—52.)

1

This invention relates broadly to mufflers for internal combustion engines and more specifically to improvements in mufflers of the type that are designed to restrain the discharge of incandescent products of combustion.

There are numerous environs in which the operation of a motor vehicle is extremely dangerous unless provision is made to safeguard the electric system and quench the sparks customarily emitted from the exhaust pipe leading from the muffler. Flour and cotton mills, oil refineries, and sea board loading docks are illustrative of a few of many enterprises that have prohibited the use of motorized material-handling equipment in the hazardous zone of their activities.

The present invention contemplates a muffler which is constructed to eliminate the emission of sparks and flames therefrom by: (1) passing the exhaust gas through a tortuous path in a heat exchanger to lower the temperature thereof, (2) deflecting the gas and cinders upon the surface of a fluid in the muffler to quench the flame or sparks entrained therein, (3) passing the gas through a spark arrester to separate or screen the solids therefrom, and (4) condensing the vaporous exhaust before discharging the gas to atmosphere.

In addition to the foregoing objects, the invention further comprehends a structure which is light in weight, economic of manufacture, efficient of operation, and capable of use without renewal of the fluid therein over relatively long periods of continuous operation.

Other objects and advantages, more or less ancillary to the foregoing, and the manner in which all the various objects are realized will appear in the following description, which, considered in connection with the accompanying drawings, sets forth the preferred embodiment of the invention.

In the drawings:

Fig. 1 is a vertical, longitudinal sectional view of the improved water muffler;

Fig. 2 is an end elevational view thereof;

Fig. 3 is a cross-sectional view of the muffler, the section being taken on a plane indicated by the line 3—3 in Fig. 1;

Fig. 4 is a horizontal sectional view through the muffler, the section being taken on a plane indicated by the line 4—4 in Fig. 1;

Fig. 5 is a diagrammatic view of the improved muffler coupled with the radiator in the vehicle.

Referring first to Fig. 1, the muffler chosen herein for purpose of illustration comprises a tank 10 of elliptic transverse section having ver-

2

tical partitions 11 and 12 adjacent the end walls 13 thereof defining respectively an intake expansion chamber 14, a fluid reservoir 15, and a discharge expansion chamber 16. The intake chamber is provided with a conduit 17 having the lower end thereof welded or otherwise affixed to a boss 18 pressed in the central portion of the partition 11. The upper end of the tube is supported by a nipple 19 mounted in the tank with the free end thereof threaded for the reception of the pipe from the engine exhaust manifold. The conduit is formed with an end closure 20, and the major portion of the side wall thereof is perforated with relatively small openings 21. The intake and discharge chambers are interconnected through one or more tubes 22 mounted in the lower portions of the partitions 11 and 12 in fluid-tight relation with the reservoir 15. The upper end of the wall 12 is pierced and formed to provide a rectangular opening 23 and an angularly disposed depending baffle 24 on the inner face thereof. The upper portion of the tank is provided with a tube or pipe 25 which constitutes the discharge passageway in the muffler. The tube is supported by a pilot boss 26 pressed in the wall 11, a flanged opening 27 in the wall 12, and a nipple 28 in the end wall 13. The end of the tube adjacent the intake chamber is closed by a cap 29 and the upper third of the wall of a substantial portion of the same end thereof is perforated with relatively small holes 30 or may be formed with slots or screened openings to restrain the entry of solid and liquid bodies and permit the egress of the gas. The free end of the nipple 28 is threaded to receive an exhaust pipe (not shown), or a condenser illustrated in Fig. 5. The central portion of the reservoir 15 is provided with a vertically disposed wall 31 constituting a baffle to dampen the surging action of the fluid within the chamber when the vehicle is in motion. The wall 31 is formed with clearance openings 32 for the tubes 22 and 25 and this wall as well as the partitions 11 and 12 and the end plates 13 are formed with marginal flanges 33 to accommodate the support thereof and reinforce the assembly.

The upper wall of the reservoir adjacent the discharge chamber is provided with a filler neck 34 having a cap 35 threaded thereon and the lower portions of the walls 11 and 13 are fabricated for the support of a drain pipe 36. The drain pipe as illustrated in Fig. 1 is threaded for the reception of a cap 37 and the inner end thereof is preferably provided with a collar 38 which is welded to the plate 11.

The muffler may be attached to the vehicle or other mechanism with which it is associated in any convenient manner, for example, through the brackets 39 and stud 40 illustrated herein. The brackets, as will be seen in Figs. 2 and 3, are formed from angle irons having the vertical legs thereof sheared to receive the base of the tank and the lateral flanges are pierced for the reception of cap screws or similar supporting means. The stud 40 is mounted in a lug 41 welded in the side wall of the reservoir adjacent the top thereof to minimize the lateral strains imposed on the cradles or brackets 39.

In practice it has been found that the improved muffler may be operated from four to eight hours before it is necessary to refill the reservoir 15 and that such operative periods may be extended by coupling a condenser 42 (Fig. 5) of any conventional form with the gas discharge outlet and draining the condensate back into the liquid reservoir. Further economies of the coolant may be realized by adding a material to the water in the reservoir which will raise the boiling point thereof, for example, an admixture of water with one of the glycols.

In the embodiment illustrated in Fig. 5, the drain pipe 36 is coupled through a conduit 50 to the engine water pump 51 and an overflow line 52 is mounted in the side wall of the reservoir at a point slightly below the lower edge of the rectangular opening 23 in the partition 12. The line 52 is coupled with the radiator inlet 53, and, if desired, a valve 54 may be interposed in the line 50 to control the flow of water or other coolant circulated by the pump 51.

In operation, the gases discharged from the engine will enter the conduit 17, pass through the openings 21 in the side wall thereof, enter the expansion chamber 14, then flow through the tubes 22 in the coolant reservoir and into the second expansion chamber 16. The gases will then pass through the opening 23, and over the face of the baffle 24, which will effect the deflection thereof over the surface of the water in the reservoir 15. Should any incandescent particles of carbon remain in the gases after the translation thereof through the tubes 22, such heated particles or sparks will be quenched since the wall 31 will arrest the flight thereof save through the upper opening 32 in the wall 31, which, it will be noted, is disposed above the lower edge of the baffle 24. After the gases pass through the opening 32 they will enter the apertures 30 in the upper face of the tube 25 and be discharged through the exhaust pipe.

From the foregoing it will be recognized that an effective silencing action will be produced as the gases pass through the several expansion chambers and the tortuous path formed by the conduits associated therewith; that the gases will be appreciably cooled while passing through the chamber 14, the tubes 22, and the chamber 16; that the sparks entrained in the stream of the gases entering the reservoir will be entrapped therein and brought into impinged relation with the water carried thereby; and that even though the reservoir should become dry, the improved organization of baffles and the perforate tube 25 will break up incandescent particles and arrest the passage of sparks therethrough.

Although the foregoing description is necessarily of a detailed character, in order that the invention may be completely set forth, it is to be understood that the specific terminology is not

intended to be restrictive or confining, and that various rearrangements of parts and modifications of detail may be resorted to without departing from the scope or spirit of the invention as herein claimed.

I claim:

1. A liquid muffler for the exhaust gases of an internal combustion engine comprising a closed vessel, a partition adjacent each end thereof defining respectively an inlet chamber, a liquid vessel, and an outlet chamber communicating with the upper portion of said vessel, a conduit in the lower portion of said vessel connecting said inlet and outlet chambers, liquid partially filling said vessel, said liquid constituting a coolant for the exhaust gases passing through the inlet chamber, said conduit, and said outlet chamber, and further constituting a quenching medium for sparks passing into said vessel, and a discharge tube in said vessel above the liquid level, said tube extending through and protruding beyond the outer wall of said outlet chamber and having a perforate side wall in the portion thereof which is disposed within the vessel.
2. A muffler for the exhaust gas from an internal combustion engine comprising a closed liquid tank, double walls in the opposed ends thereof defining gas expansion chambers, an imperforate tube in said tank connecting the lower portions of said chambers, a gas inlet in the top of one of said chambers, an outlet in the top of the other chamber communicating with said tank, a perforated outlet pipe leading from the top of said tank to and through said outlet chamber whereby the exhaust gas is cooled as it passes through the chamber and interconnecting tube and is further cooled as it passes over the surface of the liquid in said tank.
3. A muffler comprising a liquid tank having opposed double end walls defining gas inlet and outlet chambers and a central liquid vessel, a conduit connecting said chambers and extending through said vessel near the bottom thereof, a gas inlet tube in one of said chambers, an outlet in the other chamber leading into said vessel near the top thereof, baffle plates in said vessel to arrest the movement of sparks therein, and a perforated outlet pipe near the top of said vessel leading through said outlet chamber.
4. A combined muffler, heat exchanger, and spark arrester for an internal combustion engine comprising a closed tank, a partition at each end thereof defining gas inlet and outlet chambers and a central liquid reservoir, a perforated gas inlet conduit having a closed end depending to the center of said inlet chamber, an imperforate tube adjacent the lower portion of said reservoir interconnecting said chambers, an opening adjacent the top of the partition for said outlet chamber interconnecting the outlet chamber with the liquid reservoir, a baffle in said reservoir above said opening for deflecting exhaust gases downwardly into the reservoir, a gas discharge tube in the upper portion of said reservoir extending through said outlet chamber, said tube having a perforated side wall in the portion thereof within the reservoir.
5. A combined muffler, heat exchanger, and spark arrester comprising a closed tank, a partition at each end thereof defining gas inlet and outlet chambers and a central liquid reservoir, liquid partially filling said reservoir, a gas inlet conduit extending into said inlet chamber, an imperforate tube adjacent the lower portion of said

reservoir interconnecting said chambers, an opening in the top of the partition for said outlet chamber interconnecting said chamber with said reservoir, a baffle above said opening for deflecting gases downwardly into said reservoir, a gas discharge tube adjacent the top of said reservoir and said outlet chamber, said discharge tube having apertures in the upper face of the portion within the reservoir, and a perforated partition parallel the first-named partition in the center of said reservoir constituting a baffle to dampen the movement of the liquid in the reservoir.
